UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

RAILWAY CAR

Application filed July 31, 1930. Serial No. 472,165.

My invention relates to railway cars and more particularly to the embodiment therein of means adapted to serve as a support for a load lifting device whereby heavy and cumbersome articles such as automobiles, machinery and the like may be moved into and out of the car or elevated within the car to permit a platform, rack or similar support to be placed thereunder.

10 A principal object of the invention is to provide the car with a longitudinally extending substantially channel shaped beam to which members are rigidly secured, each of the members forming with the beam a structure of box-like section and being adapted to serve as a support for a load lifting device.

Another object of the invention is to rigidly connect the longitudinally extending channel shaped beam to the carlines of the car 20 by members having portions forming with the beam structures of box-like section which are adapted to serve as supports for load lifting devices.

Another object of the invention is to associate the longitudinally extending beam with the car in such manner, that in addition to serving as means to which members for supporting load lifting devices may be attached, performs the usual functions of a ridge pole 30 by bracing the roof of the car against distortion and by supporting the roof sheets.

Other and more specific objects of the invention residing in advantageous forms, combinations and relations of parts will herein- 35 after appear and be pointed out in the claims.

In the drawings illustrating preferred embodiments of the invention:

Figure 1 is a longitudinal sectional view of the car roof of a railway box car.

40 Figure 2 is a transverse fragmentary sectional view of the car roof.

Figure 3 is an enlarged sectional view taken on line 3—3, Figure 1.

Figure 4 is a sectional view taken on line 45 4—4, Figure 3.

Figure 5 is an enlarged sectional view taken on line 5—5, Figure 1.

Figure 6 is a view corresponding to Figure 1 illustrating a modified form of the invention.

Figure 7 is a view corresponding to Figure 2 illustrating the modified form of the invention shown in Figure 6.

Figure 8 is an enlarged sectional view taken on line 8—8, Figure 6.

Figure 9 is a sectional view taken on line 9—9, Figure 8.

Figure 10 is an enlarged sectional view taken on line 10—10, Figure 6.

Figure 11 is a view corresponding to Figure 1 showing still another modified form of the invention.

Figure 12 is a view corresponding to Figure 2 illustrating the modified form of the invention shown in Figure 11.

Figure 13 is an enlarged sectional view taken on line 13—13, Figure 11.

Figure 14 is a sectional view taken on line 14—14, Figure 13.

Referring more particularly to the drawings the invention is shown in Figures 1 to 5, inclusive, in connection with a car roof of the flexible type which comprises rigidly connected side plates 1 and end plates 2. The side plates are connected to each other by carlines which are preferably of channel shape having a web 3 and downwardly extending legs 4 terminating in oppositely disposed laterally projecting flanges 5. The spaces between the carlines are spanned by roof sheets 6 which may advantageously extend continuously from one side of the car to the other. Along their side edges the roof sheets are fashioned with upturned flanges 7 for cooperating with seam caps 8 which are rigidly secured to the carlines in embracing overlapping relation by roof clamps 9 which may be of any suitable design.

Extending longitudinally of the car beneath the roof sheets adjacent the ridge of the roof is a beam 10 of inverted channel shape having a substantially horizontal web 11 and downwardly extending legs 12 which terminate in oppositely disposed laterally projecting flanges 13. At its opposite ends the beam is rigidly connected to the end plates 2 by brackets 14 which may be conveniently formed of angle shape. These brackets are respectively secured to the end plates by 100

rivets 15 and to the beam by rivets 16 which pass through its lateral flanges 13.

Intermediate its ends the beam is rigidly connected to the carlines by members 17, each 5 of which is formed with a substantially horizontal portion 18 extending beneath the beam and rigidly secured by rivets 19 to the flanges 13 thereof. The end portions 20 of each bracket are attached to the web 3 of the carline by rivets 21, the portions of the web adjacent these rivets being recessed as at 22 so that the rivet heads will not project above the upper surface of the carline. The horizontal portion 18 and end portions 21 of each 10 bracket are integrally connected by substantially vertical leg portions 23. If desired, the brackets may be rigidified by side marginal flanges 24. Intermediate the carlines the beam 10 is provided with a plurality of members 25 which extend transversely of the car and are rigidly secured to the lateral flanges 13 of the beam by rivets 26. Each of these 15 members is preferably formed with a substantially horizontal plate portion 27 and with downwardly extending marginal flanges 28. As may be perceived the plate portion 27 of each of the members 25 is spaced a sufficient distance from the adjoining web portion 11 of the beam so that a load lifting device may 20 be supported thereby by passing a rope or chain or the nose of a hook through the space or opening defined by the web 11 of the beam and the portion 27 of the member 25. The portions 18 of the beam supporting brackets 25 25 are arranged in a manner similar to the portions 27 of the members 25 so that a load lifting device may be likewise supported therefrom. As the members 25 and the brackets 17 extend transversely of the beam and 30 are rigidly secured to the flanges of the latter they form with the beam structure of box-like section. By arranging the load lifting members in this manner the beam is rigidified against distortion and bending which would 35 otherwise result from the forces transmitted to it from the load lifting devices.

By positioning the beam 10 in the manner shown in the drawings it will be perceived that it is capable of functioning as a ridge 50 pole in that it braces the roof against distortion and affords convenient means for supporting the roof sheets. Furthermore, since the beam as well as the brackets 17 and members 25 are located considerably above a plane 55 passing through the ends of the carlines the beam and its attachments will not interfere with the loading of lading within the car.

In Figures 6 to 10, inclusive, the invention 60 is shown as applied to a roof of the rigid type, namely, one in which the roof sheets are rigidly connected to the carlines. In this embodiment of the invention the roof sheets 6 are formed with upwardly projecting substantially vertical flanges 29 which are embraced 65 by and secured to carlines 30. Each of these

carlines is formed with downwardly extending legs 31 between which the flanges 29 of the roof sheets are secured by rivets 32 and with oppositely disposed laterally projecting flanges 33 arranged in overlapping relation to adjacent portions of the roof sheets. As in Figures 1 to 6 of the drawings the beam 10 is supported by brackets 17 but their end portions are slightly modified so as to afford substantially vertical portions 34 which are interposed between adjacent flanges of the roof sheets and secured to the latter and the legs 31 of the carlines by adjacent rivets 32.

In Figures 11 to 14, inclusive, the invention is shown as applied to still another type of rigid roof. In this form of the invention the carlines are of the same shape as those shown in Figures 1 to 5, but instead of employing a seam cap for flexibly connecting the carlines and roof sheets the latter are formed with channel shaped portions 35 arranged in embracing overlapping relation with the carlines and rigidly secured thereto by roof clamps 36. The brackets 17 for connecting the beam and the carlines may be dispensed with and the beam connected directly to the carlines by rivets 37 which pass through the lateral flanges 5 of the latter and the web portion 11 of the beam. This manner of connecting the beam and carlines greatly rigidifies the roof structure as portions of the beam adjacent the carlines form with the latter structure of box-like section so that distortion of the carlines by spreading of the legs 4 thereof is effectively prevented. As in this form of the invention the connecting brackets 17 are omitted the beam 11 may be provided with additional members 25 immediately below the carlines.

Although the drawings illustrate various forms of the invention it is to be understood that the invention is not limited to the exact details of construction illustrated and described as various changes may be made without departing from the spirit of the invention as defined by the following claims.

I claim:

1. A roof for railway cars involving a plurality of carlines, a beam of inverted channel shape extending longitudinally of the car beneath the carlines, and a plurality of members extending transversely of and fixedly secured to the beam, each of said members forming with the beam a structure of box-like section and being adapted to serve as a support for a load lifting means.

2. A roof for railway cars having a plurality of transversely extending substantially channel shape rigidifying portions, a beam of inverted channel shape extending longitudinally of the car beneath the carlines, and a plurality of members extending substantially parallel with said rigidifying portions and rigidly secured to the beam, each of said members forming with the beam a structure

of box-like section and being adapted to serve as a support for a load lifting means.

3. A roof for railway cars involving a plurality of carlines, roof sheets spanning the spaces between the carlines, a beam of inverted channel shape extending longitudinally of the car beneath the carlines, said beam being in supporting engagement with the undersides of the roof sheets, and a plurality of members extending transversely of and rigidly secured to the beam, each of said members forming with the beam a structure of box-like section and being adapted to serve as a support for a load lifting means.

15 4. A roof for railway cars involving carlines, a beam of inverted channel shape extending longitudinally of the car beneath the carlines, said beam being provided with oppositely extending laterally projecting flanges, and a plurality of members extending transversely of the beam and rigidly secured to the flanges of the latter, each of said members forming with the beam a structure of box-like section and being adapted to serve as a support for a load lifting means.

20 5. A roof for railway cars involving carlines, a beam extending longitudinally of the car beneath the carlines, said beam being of substantially channel shape and comprising a web and downwardly extending legs, and a plurality of members extending transversely of and rigidly secured to the beam, each of said members being provided with a portion disposed in spaced relation to the web 25 of the latter constituting means for supporting a load lifting device.

6. A roof for railway cars involving a plurality of carlines, a beam extending longitudinally of the car beneath the carlines, said beam being of substantially channel shape and comprising a web and downwardly extending legs terminating in oppositely projecting laterally extending flanges, and a plurality of members extending transversely of 45 the beam and rigidly secured to the flanges thereof, each of said members having a portion disposed in spaced relation to the web of the beam constituting means for supporting a load lifting device.

50 7. A roof for railway cars involving carlines, a beam of substantially channel shape extending longitudinally of the car beneath the carlines, and a plurality of members rigidly secured to the beam and extending transversely thereof intermediate the carlines, each of said members forming with the beam a structure of box-like section and being adapted to serve as a support for a load lifting means.

60 8. A roof for railway cars involving a plurality of inverted channel shape carlines, a beam of inverted channel shape extending longitudinally of the car beneath the carlines and rigidly connected to the latter, said beam having oppositely disposed laterally

projecting flanges, and a plurality of members extending transversely of the beam and rigidly secured to the flanges thereof, each of said members forming with the beam a structure of box-like section and being adapted to serve as a support for a load lifting means.

9. A roof for railway cars involving a plurality of carlines, a beam of substantially channel shape extending longitudinally of the car beneath the carlines, and means connecting said carlines and beam involving a member extending beneath the latter and having a portion forming with the beam a structure of box-like section adapted to serve as a support for a load lifting means.

10. A roof for railway cars involving a plurality of carlines, a beam of substantially channel shape extending longitudinally of the car beneath the carlines, said beam being provided with oppositely disposed laterally projecting flanges, and a plurality of members extending beneath the beam and rigidly secured to the flanges of the latter and to the carlines, each of said members having a portion forming with the beam a structure of box-like section and being adapted to serve as a support for a load lifting means.

11. A roof for railway cars involving a plurality of carlines respectively having downwardly extending legs, a beam extending longitudinally of the car beneath the carlines, and means for rigidly connecting the beam and carlines comprising a plurality of members respectively extending beneath the beam and rigidly secured to the carlines between the legs of the latter, each of said members having a portion forming with the beam a structure of box-like section and being adapted to serve as a support for a load lifting means.

12. A roof for railway cars involving a plurality of carlines, each of said carlines being of channel shape and comprising a web and downwardly extending flanges, a beam of substantially channel shape extending longitudinally of the car beneath the carlines, and a member extending beneath the beam and having its ends rigidly secured to the web of an adjacent carline, said member having a portion forming with the beam a structure of box-like section and being adapted to serve as a support for a load lifting means.

13. A roof for railway cars involving a plurality of inverted channel shape carlines, a beam extending longitudinally of the car beneath the carlines, means for supporting said beam involving members respectively extending beneath the latter and rigidly secured to the carlines, and a plurality of brackets extending transversely of the beam and rigidly secured to the latter intermediate the carlines, each of said members and brackets having a portion forming with the beam a structure of box-like section and being

adapted to serve as a support for a load lifting means.

14. A roof for railway cars involving a plurality of carlines, each of said carlines having downwardly extending legs, a beam extending longitudinally of the car beneath the carlines, and means for supporting said beam involving a plurality of members, each of said members extending beneath the beam and rigidly secured to both legs of an adjacent carline, each of said members being provided with a portion forming with the beam a structure of box-like section and being adapted to serve as a support for a load lifting device.

15. A roof for railway cars involving a plurality of carlines, a beam of substantially channel shape extending longitudinally of the car beneath the carlines, and a plurality of members for supporting said beam, each of said members having a substantially horizontal portion extending beneath the beam and a plurality of transversely extending vertical end portions rigidly secured to an adjacent carline, each of said horizontal portions forming with the beam a structure of box-like section and being adapted to serve as a support for a load lifting means.

16. A roof for railway cars involving a plurality of carlines each of said carlines being of channel shape and comprising a web and downwardly extending legs the latter being provided with oppositely disposed laterally extending flanges and a beam extending longitudinally of the car and rigidly secured to the flanges of the carlines said beam being of inverted channel shape and having a plurality of transversely extending members fixedly secured thereto, each of said members forming with the beam a structure of box-like section and being adapted to serve as a support for a load lifting means.

17. A roof for railway cars involving a plurality of carlines having oppositely disposed laterally projecting flanges, a beam of channel shape extending longitudinally of the car beneath the carlines, said beam comprising a web and downwardly extending legs terminating in laterally projecting flanges, the web of the beam being rigidly secured to the lateral flanges of the carlines, and a plurality of members extending transversely of the beam and rigidly secured to the flanges of the latter, each of said members forming with the beam a structure of box-like section and being adapted to serve as a support for a load lifting means.

18. A roof for railway cars involving a plurality of carlines, a beam of substantially inverted channel shape extending longitudinally of the car beneath the carlines, and a plurality of members extending transversely of and rigidly secured to the beam, each of said members having a portion forming with the beam a structure of box-like section and

being adapted to serve as a support for a load lifting means, the said portions of each of said members being provided with downwardly extending flanges.

19. A roof for railway cars involving a plurality of carlines, a beam of substantially inverted channel shape extending longitudinally of the car beneath the carlines, and a plurality of members extending transversely of and rigidly secured to the beam, each of said members having a portion forming with the beam a structure of box-like section and being adapted to serve as a support for a load lifting means, the said portion of each of said members having a substantially horizontally disposed plate portion provided with downwardly extending marginal flanges.

In testimony whereof I affix my signature.

EARL R. SWANSON.
